DETACHABLE SHEET METAL LINK AND
LINKAGE FORMED THEREFROM

Karl C. Augenstein, Cranston, R.I., assignor to Speidel Corporation, Providence, R.I., a corporation of Rhode Island

Filed July 11, 1958, Ser. No. 747,876
8 Claims. (Cl. 59—80)

The present invention relates to an improved band of pivotally attached links for use as a wrist watch strap, bracelet or the like. More particularly the invention relates to such a band at least a part of which comprises a plurality of pivotally attached non-expansile links.

An object of the present invention is to provide such a band in which adjacent links are pivotally connected by a simple, inexpensive and unique mechanism by means of which such links are readily detachable from an attachable to each other without the use of special tools and without the necessity of returning the bracelet to the factory. Consequently, one or more links can be readily removed or inserted by the jeweler to shorten or lengthen the bracelet or to repair the removed link or links.

Another object is to provide such a mechanism in which the danger of the links becoming detached by accident is reduced to a minimum. However, its operation is simple and obvious to even an unskilled person to whom it has been disclosed.

Another object is to provide such a mechanism that is simple but rugged in construction and is simple and inexpensive to make.

Another object is to provide such a band in which the mechanism for detachably attaching the links comprises a separable, pivotal hinge attachment between adjacent links.

Another object is to provide a link having a mechanism for pivotally and detachably attaching the link to an adjacent link or other member. Preferably, the mechanism comprises a part which is mounted in the link and which is movable to a first attach position in which it completes a separable, pivotal connection between the link and its adjacent link or member and to a second detach position in which the separable, pivotal connection is separated and the link can be detached from its adjacent link or other member. In a preferred form of the invention the part comprises a longitudinally slidable hinge pin.

Another object is to provide such a link which includes self contained resilient means for resiliently urging and normally maintaining such movable part to and in its attach position.

Another object is to provide such a link in which the movable part is adapted to be forced from attach position to detach position against the force of said resilient means urging it to its attach position.

Another object is to provide such a link which is hollow, in which the resilient means urging the movable part to its attach position is located within the hollow link, and in which the movable part is slideable within the hollow link between its attach position, in which it protrudes a substantial distance out of a side edge of the hollow link to complete the separable, pivotal connection, and its detach position in which it is retracted further into the hollow link to separate the separable pivotal connection.

Another object is to provide such a link in which the resilient means comprises a spring element which is sinusous, preferably sinusoidal, in shape, and which extends generally in a direction transverse to the longitudinal center line of the band.

Another object is to provide such a link in which the sinusous shaped resilient spring element has two sets of folds. The folds of each set are substantially coplanar.

The plane of each set of folds is substantially parallel to the plane of the other set and is substantially transverse to the longitudinal center line of the band. The folds of each set are connected by parts of the spring element which extend generally transverse to the planes of the folds.

Another object is to provide such a link in which the movable part comprises a hinge pin which is integral with and forms an end portion of such spring element and extends in a direction generally transverse to the longitudinal center line of the band.

Another object is to provide such a link in which the hinge pin is aligned with one of the sets of folds and in which a portion of the spring element intermediate its ends is exposed for applying a force thereto to force the pin from its attach position to its detach position against the force exerted on it by the sinusous portion of the element.

Another object is to provide such a link in which the exposed portion of the spring element extends in the general direction of the longitudinal center line of the band, the pin extending at about a right angle from such exposed portion in a direction transverse to said longitudinal center line.

Another object is to provide such a link having a notch in a wall thereof, such notch overlying and exposing said exposed portion of the spring element.

Another object is to provide such a link in which the hinge pin protrudes into a recess in an edge of the link and is received in a hinge portion of the next adjacent link or member, such hinge portion being received in the recess.

Another object is to provide such a link which has a hinge portion extending from the edge thereof opposite from that having the recess and in the direction of the longitudinal center line of the band, the last mentioned hinge portion being received in a recess in the other adjacent link or member.

Another object is to provide such a link in which the spring element has a hinge pin at its other end extending in a direction generally transverse to the center line of the band, in which the sinusous shaped part of the element comprises an intermediate part thereof and the two hinge pins comprise end portions thereof and in which the two hinge pins of the spring element protrude beyond opposite side edges of the link into recesses in an edge of the link facing the next adjacent link or member, such pins being received in hinge portions of the next adjacent link or member, such hinge portions being received in the recesses, whereby the link is pivotally and detachably attached to the adjacent link or member.

Another object is to provide such a link which has a pair of hinge portions extending from the edge thereof opposite from the edge having the recesses and in the direction of the longitudinal center line of the band, such last mentioned hinge portions being adapted to receive hinge pins of the other adjacent link or member and being received in a pair of recesses in the other adjacent link or member, whereby the link is pivotally and detachably attached to the other adjacent link or member.

Another object is to provide such a link having means for cooperating with the adjacent links or members for limiting pivotal movement with respect thereto.

Another object is to provide such a link having a top shell which overlaps one of the adjacent links or members to limit pivotal movement therebetween in one direction and a displaced portion on the bottom wall thereof which overlaps the bottom of the other adjacent link or member to limit pivotal movement therebetween in an opposite direction.

Another object is to provide a band comprising a plurality of such links pivotally and detachably attached

to each other by means of such detachable hinge portions and hinge pins.

Another object is to provide a novel and improved link which is pivotally and detachably attachable to an adjacent member and a novel and improved band comprising a plurality of such links pivotally and detachably attached to each other.

Other objects and advantages will be apparent from the following description and accompanying drawings in which:

FIG. 1 is a top plan view of a band of links embodying an embodiment of the present invention with the expandable part of the band in partially expanded position.

FIG. 2 is an enlarged top plan view of a non-expandable end section of the band of FIG. 1 with the ornamental top shells of some of the non-expandable links removed.

FIG. 3 is an enlarged bottom view like FIG. 2 partially in section.

FIG. 4 is a view like FIG. 3 showing the non-expandable end section fully detached at one place and partially detached at another.

FIG. 5 is a side view of the band of FIG. 3 partially in section.

FIG. 6 is a section taken along the lines 6—6 of FIG. 3 and rotated 180° about the longitudinal center line of the band.

FIG. 7 is a section taken along the line 7—7 of FIG. 3.

FIG. 8 is a section taken along the line 8—8 of FIG. 3.

FIG. 9 is an exploded perspective view of one of the links of the non-expandable section.

FIG. 10 is a perspective view of the hollow link of FIG. 9 taken from a different direction.

FIG. 11 is a perspective view of the hollow link of FIG. 10 with the sheet material from which the link is made being only partially bent towards the position it occupies in the link.

Referring now to the drawings:

Band 2 (FIG. 1) comprises a pair of non-expandable end sections 4 comprising a plurality of non-expandable links 6, pivotally attached to each other in a novel manner to be described hereinafter, and an expandable middle section 10 comprising a plurality of upper and lower expandable links 8 and 12 respectively arranged in a lazy tong arrangement. The lazy tong expandable linkage per se does not constitute part of the present invention and consequently, it will not be described in detail. The expandable section 10 is attached by a half link 13 and a quarter link 15 to the bottom of terminal connector 14, which is in turn attached to one end of a non-expandable end section 4 in a manner to be described hereinafter.

Each non-expandable link 6 comprises a hollow link 16 having an ornamental shell 18 attached to the top thereof and a spring element 20 by means of which the link is detachably and pivotally attached to its adjacent link in a manner to be described hereinafter. Each hollow link 16 is made of a single piece or blank of sheet metal such as steel, which is bent into a hollow middle tubular portion 22 (see FIGS. 9, 10 and 11) having a relatively flat upper wall 24, a relatively flat bottom wall 26, a pair of end walls 28 and 30 formed by bends in the metal, as shown, and open sides 31. The edges of the sheet come together at 32 to form a seam. The end wall 28 and the adjacent portion of upper wall 24 have a notch 34 cut therein intermediate their ends, as shown. The portion of bottom wall 26 opposite notch 34 in the top wall has a downwardly displaced portion 36 extending to the end wall 28 and having a lip 38, which extends beyond the end wall 38 in the direction of the longitudinal center line of the band and which is displaced slightly upwardly from the bottom wall of the downwardly displaced portion 36, as shown. Lip 38 is slightly below the plane of the bottom wall 26.

The middle tubular portion 22 of the hollow link 16 has a pair of side wing portions 40 extending from each side thereof, such side portions 40 being offset from the

middle tubular portion 22 in the direction of the longitudinal center line of the band, as shown, to form a pair of recesses 42 in the opposite ends of one edge 43 (formed by wall 28) of the link 16 and protruding portions 41, which protrude from the opposite ends of the edge 43 (formed by wall 30) of link 16 opposite from edge 43 in the direction of the longitudinal center line of the band, as shown, and which form a pair of hinges 46. Hollow link 16 may be described as being generally U shaped with recesses 42 in the outer corners of the U formed by the base 22 of the U and the legs 41 and each leg 41 having a hinge 46.

Each side portion 40 comprises an integral extension of a part of the side 31 of the bottom wall 26 adjacent end wall 30, which extension is displaced from bottom wall 26 upwardly at 44, extends beyond end wall 30 in the direction of the longitudinal center line of the band to form protruding portion 41 and is folded upwardly at 46 back on itself at 48 to form a hinge. Portion 46 extends along the upper surface of portion 44 and is located slightly below the plane of the upper wall 24 of the hollow link, as shown in FIG. 10. The shoulder 49 (FIG. 9) formed by the juncture of the side of bottom wall 26 and the upwardly displaced portion 44 of each side portion 40 together with the inner edge 51 (FIGS. 10 and 11) of 48 of such side portion overlie a substantial portion of the open side 31 of middle tubular portion 22 adjacent end wall 30.

Each recess 42 has a wall 50, extending in a direction transverse to the longitudinal center line of the band and formed by the edges of 44 and 48, and a wall 52 extending in the direction of the longitudinal center line of the band and formed by the portion of the open side 31 of middle hollow portion 22 adjacent end wall 28.

It is noted that end wall 30 of middle portion 22 and the inner edges 60 of protruding portions 41 form a tongue-receiving recess 58, and that the part of middle tubular portion 22 between recesses 42 forms a hollow tongue 64, the open sides 31 of portion 22 adjacent wall 28 comprising openings 69 in the sides of the hollow tongue 64. The hollow tongue 64 of each hollow link 16 is received in the tongue-receiving recess 58 of one of its next adjacent links with the hinges 46 of such next adjacent link 16 being received in the recesses 42 of the link. The tongue-receiving recess 58 of such link receives the hollow tongue 64 of the other adjacent link with the hinges 46 of such link being received in the recesses 42 of the other adjacent link.

One of the side edges of the bottom wall 26 of the middle tubular portion 22 forming recess wall 52 has a notch 73 therein which is elongated in a direction generally transverse to the longitudinal center line of the band, as shown. A portion of the edges 49, 51 of the side portion 40 lie over the opening of the notch 73, such edges being beveled slightly at 74, as shown, to provide access to the notch opening.

A resilient spring element 20 is located within the hollow middle portion 22 of link 16. Spring element 20 has a middle, sinuous or sinusoidal shaped spring portion 65, each end of which extends integrally into a pin 71 and 72. The sinuous shaped, middle portion 65 comprises an elongated strip of resilient flat material such as spring steel having a plurality of folds 67 therein divided into two sets 66 and 68, the folds of each set being substantially coplanar and the plane of the folds of each set being substantially parallel to the plane of the folds of the other set and extending in a direction generally transverse to the longitudinal center line of the band. The spring element 20 extends generally in a direction transverse to the longitudinal center line of the band. Opposite folds 66 and 68 are connected by the cross pieces 75 which extend in a direction generally transverse to the planes of the folds and generally parallel to the longitudinal center line of the band. Each end pin 71 and 72 is circular in cross-sectional shape and

extends in an opposite direction from the other. Both end pins extend in a direction generally transverse to the longitudinal center line of the band, as shown. Spring element 20 is snugly received in the hollow middle portion 22 of the hollow link 16 with one set of folds 66 lying along and adjacent to the slotted end wall 28 of the middle portion and the other set of folds 68 lying along and adjacent to the end wall 30. Notch 34 exposes some of the folds 66. Engagement of the cross pieces 75 of the spring element 20 from which pins 71 and 72 extend with the shoulders 49 and edges 51 of side portions 40 prevent the spring element from sliding out of the sides of hollow middle portion 22. Pin ends 71 and 72 are generally perpendicular to the cross pieces 75 from which they integrally extend, are aligned and coplanar with the set of folds 66 and protrude out of the openings 69 at the sides of the hollow tongue 64 and hence out of the recess walls 52 of the recesses 42 into the recesses, as shown, each pin being spaced in the direction of the longitudinal center line of the band from the other recess wall 50, as shown.

Pins 71 and 72 of each link 16 are pivotally received in the apertures 77 of the hinges 46 of the side portions 40 of the next adjacent link 16, such hinges being received in the recesses 42 of said each link, as shown. These pins 71 and 72 therefor comprise hinge pins for these hinges. The hinge pins 71 and 72 of the other adjacent link 16 are received in the apertures 77 of hinges 46 of said each link, such hinges being received in the recesses 42 of said other adjacent link, as shown. Consequently, each link 16 is pivotally attached or connected to one adjacent link by means of its hinge pins 71 and 72 and the hinges 46 of such next adjacent link and is pivotally attached or connected to its other adjacent link 16 by means of its hinges 46 and the hinge pins 71 and 72 of the other adjacent link. The pivotal axis of each hinge connection extends in a direction from one side of the band to the other and generally transverse to the longitudinal center line of the band. The edges 73a of the side portions 40 form the sides of the band.

The cross piece 75 of spring element 20 from which the pin 71 extends is exposed by the notch 73 and is located close to the open end of the notch, as shown. The notch 73 and beveled portions 74 of side portion 40 permit the pointed end of a pointed object 79 such as a common pin or the like to be placed against the outer wall of the exposed cross piece 75 and to be moved inwardly toward the longitudinal center line of the band to compress the intermediate sinuous shaped spring portion 65 of the spring element 20, as shown in FIGS. 3 and 4, and to force hinge pin 71 to move inwardly and longitudinally against the force exerted thereon by the intermediate spring portion 65 from attach position, which is shown in FIGS. 2 and 3, in which it is normally maintained by the shape of the spring element 20 and in which the pin 71 protrudes from the wall 52 of recess 42 into the recess and is received in hinge 46 of the next adjacent link, whereby a separable, pivotal connection is provided between the two links, to a detach position, as shown in FIGS. 3 and 4, in which the pin 71 is retracted into the middle tubular portion 22 and is removed from the hinge 46 of the next adjacent link, whereby the separable pivotal connection is separated and the two links can be detached from each other by moving the hinge 46 out of the recess 42, as shown in FIG. 4, whereafter the pin 72 can be moved out of its hinge 46 of the adjacent link. The engagement of the shoulder 49 and edge 51 of side portion 40 with cross piece 75 from which the opposite pin 72 extends prevents the spring element 20 from being forced sideways out of the hollow intermediate portion 22 while the pin 71 is being forced inwardly, as aforesaid.

The link can be detached from its other adjacent link in the same way and the two adjacent links can be pivotally attached to each other to thereby shorten the

length of the band by first inserting the pin 72 of the other adjacent link into its corresponding hinge 46 of the first adjacent link, as shown in FIG. 4, thereafter forcing pin 71 of the other adjacent link to its detach position by member 79 and while holding it in detach position moving the other hinge 46 of the first adjacent link into the corresponding recess of the other adjacent link and finally releasing pin 71, whereby the spring portion 65 forces pin 71 into the aperture of the last mentioned hinge 46 to complete a pivotal connection therebetween.

Lip 38 of each link underlies the bottom wall 26 of its right hand adjacent link 16, as shown in FIGS. 5 and 6, to thereby function as a stop to limit the amount of pivotal movement which can take place between the two links in a downward direction, the pivotal movement therebetween in the other direction being limited by a stop mechanism to be described hereinafter.

Ornamental shell 18 is attached to the top of each hollow link 16 by means of a pair of tabs 76 extending downwardly from the side walls 78 of the shell and under the link 16, as shown, each tab 76 being received in the recess in the bottom of link 16 formed by the upwardly displaced side portion 44, as shown. The side walls 78 of the ornamental shell overlie the sides 73a of the hollow link 16, as shown, with the corner portions 80 thereof overlying a part of the apertures 77 of the hinges 46 (see FIG. 5). A recess 82 is provided in an edge of each side wall 78 opposite from the edge having the corner portion 80 and conforms in shape generally to the outline of an adjacent part of the hinge 46 of the next adjacent link.

The longitudinal edges of upper wall 84 of ornamental shell 18 are corrugated and generally curvilinear, as shown. A portion of the upper wall 84 of the ornamental shell of each link overlaps the top wall 24 of the middle portion 22 of the left hand adjacent link to provide a stop for limiting pivotal movement of the two links with respect to each other in an upward direction. The ornamental shell of the right hand adjacent link overlaps the top of the link to provide a stop for limiting such pivotal movement therebetween and the lip 38 of the left hand adjacent link overlaps the bottom wall of the link to provide a stop for limiting pivotal movement therebetween in a downward direction. The longitudinal edges of upper wall 84 have flanges 86 depending downwardly therefrom. The flanges 86 are corrugated in the same way as the longitudinal edges of the upper wall. The corrugated flanges 86 of the ornamental shells of adjacent links interfit with each other, as shown.

The pins 71 and 72 of the end link 16 which is attached to terminal member 92 form hinge pins for a pair of hinges 90 (see FIGS. 3, 4 and 5) of terminal member 92, the hinges 90 being formed in a pair of protrusions 94, which protrude from the end portions of an edge 95 of the hollow main body 96 of the terminal member 92. Body 96 forms a hinge for receiving the bail of a watch and has a tongue 103 extending from the mid portion of edge 95 in the same general direction as the protrusions 94. The tongue 103 has an end portion 110 which is bent downwardly and which cooperates with the lip 38 of the end link 16 to limit pivotal movement of the terminal connector 92 with respect to the end link downwardly.

Terminal member 92 has an ornamental shell 100 conforming generally to the shape thereof and extending thereover. The ornamental shell 100 is attached to the terminal member by means of tabs 102 and the portion 104 (see FIG. 5) which is bent around the outside of the body 96 of the terminal member, as shown. A part 103 of the shell 100 overlaps the top of the end link 16 to limit pivotal movement between the terminal member and end link in an upward direction. The top of the overlapping part 103 of the shell 100 conforms in design with the tops of the other shells 18.

The other end link of the non-expansible section is pivotally attached to the terminal connector 14 of the expansible section 10 by means of a hinge pin 114 which is received in a hinge 112 of the connector 14 and hinges 118 of the ornamental shell 120 of said other end link. This ornamental shell 120 is different from the other ornamental shells 18 in that it has an extended portion 122 which extends substantially beyond the hinges 46 of such end link, and from which hinges 118 extend, as shown. A pin 124 extends along the width of the bracelet and is received by the hinges 46 of the end link, as shown. The ends of the pin 124 extend through apertures in the side walls 78 of the ornamental shell 120 and are peened over at 125 (FIG. 4). This arrangement strengthens the connection between the end link 16 and the terminal connector 14 of the expansible section.

Although I have shown and described a desirable embodiment of the invention, it will be apparent to persons skilled in the art that various changes in shape, proportion and arrangement of the parts as well as the substitution of equivalent elements may be made without departing from the spirit or scope of the invention as set forth in the appended claims.

I claim:

1. A hollow link for use in a band of links, said link comprising a strip of sheet metal bent in the form of a hollow loop open at its sides and the axis of which extends in a direction substantially transverse to the direction of the longitudinal center line of the band, a strip of metal extending outwardly in said transverse direction from the portions of the opposite open sides of said loop adjacent one end wall to form a pair of wings, each of said strips forming said wings extending beyond said one end wall of said loop in the direction of the longitudinal center line of the band and then bending backwardly on itself to form a hinge loop at the bend thereof offset in said last mentioned direction from said one end wall and adapted to cooperate with hinge pins of a first adjacent member to provide a pivotal connection therebetween, the edges of said wings adjacent said open sides of said loop closing the portions of said open sides from which they extend, said wings forming with the remaining open sides of said loop adjacent the other end wall a pair of recesses, a spring element located in said hollow loop and extending in a direction transverse to the longitudinal center line of the band from one side of the loop to the other, said spring element comprising a resilient sinusoidal shaped mid-portion having hinge pins extending from the opposite ends thereof out of said open sides of said loop and into said recesses for cooperating with hinge loops of a second adjacent member adapted to be received within said recesses to provide a separable pivotal connection between said link and second adjacent member, said sinusoidal mid-portion of said spring element comprising a plurality of folds connected by cross pieces which extend in the general direction of the longitudinal center line of the band, said pins extending from the end cross pieces of said mid-portion, a slot in said loop extending in said transverse direction and exposing at least one of said end cross pieces whereby said sinusoidal portion of said element can be compressed to retract at least one of said pins into said loop and out of its recess and the hinge loop of the second adjacent member received within said recess to separate the pivotal connection formed by said pin and hinge loop, said end cross pieces abutting against the edges of said wings which close said portions of said open sides to prevent the spring from moving longitudinally out of the loop.

2. A linkage comprising a link according to claim 1 in combination with said adjacent members, said adjacent members comprising links of substantially the same construction as said link, said hinge loops of said link fitting in the recesses of said first adjacent link and being aligned with the open sides of the loop of said first adjacent link

and receiving the hinge pins of the spring element in the loop of said first adjacent link, the hinge loops of said second adjacent link being received within said recesses of said link and being aligned with the open sides of the loop of said link and receiving the hinge pins of the spring element of said link, said hinge loops of said links fitting relatively snugly around said pins but loosely enough to provide freedom of rotational movement therebetween.

3. A link according to claim 1, said slot being in an open side of said link forming a wall of one of said recesses.

4. A hollow link for use in a band of links, said link comprising a strip of sheet metal bent in the form of a hollow loop open at its sides and the axis of which extends in a direction substantially transverse to the direction of the longitudinal center line of the band, a strip of metal extending outwardly in said transverse direction from the portions of the opposite open sides of said loop adjacent one end wall to form a pair of wings, each of said strips forming said wings extending beyond said one end wall of said loop in the direction of the longitudinal center line of the band and then bending backwardly on itself to form a hinge loop at the bend thereof offset in said last mentioned direction from said one end wall and adapted to cooperate with hinge pins of a first adjacent member to provide a pivotal connection therebetween, the edges of said wings adjacent said open sides of said loop closing the portions of said open sides from which they extend, said wings forming with the remaining open sides of said loop adjacent the other end wall a pair of recesses, a spring element located in said hollow loop and extending in a direction transverse to the longitudinal center line of the band from one side of the loop to the other, said spring element comprising a resilient sinusoidal shaped mid-portion having hinge pins extending from the opposite ends thereof out of said open sides of said loop and into said recesses for cooperating with hinge loops of a second adjacent member adapted to be received within said recesses to provide a separable pivotal connection between said link and second adjacent member, said sinusoidal mid-portion of said spring element comprising a plurality of folds connected by cross pieces which extend in the general direction of the longitudinal center line of the band, said pins extending from the end cross pieces of said mid-portion, a slot in said loop extending in said transverse direction and exposing at least one of said end cross pieces whereby said sinusoidal portion of said element can be compressed to retract at least one of said pins into said loop and out of its recess and the hinge loop of the second adjacent member received within said recess to separate the pivotal connection formed by said pin and hinge loop, said end cross pieces abutting against the edges of said wings which close said portions of said open sides to prevent the spring from moving longitudinally out of the loop, said loop having a bottom wall having a downwardly offset portion adjacent said other end wall, said offset portion protruding beyond said other end wall in the direction of the longitudinal center line of the band and under said second adjacent member.

5. A link according to claim 4, also including a top shell on top of said link, said top shell protruding beyond said one end wall in the direction of the longitudinal center line of said band and over said second adjacent member.

6. A link according to claim 1, said folds comprising two sets of folds, the folds of each set being coplanar, the plane of each set being substantially parallel to the other set and extending substantially transverse to the longitudinal center line of said band, said pins being coplanar with one of said sets of folds.

7. A link according to claim 6, said other end wall having a slot therein exposing a plurality of folds lying adjacent thereto.

8. A link according to claim 7, said mid-portion of said spring element comprising a flat strip of resilient mate-

rial bent into said folds, said pins being circular in cross-sectional shape.
